UNITED STATES PATENT OFFICE.

LOUIS B. HASBROUCK, OF ELMIRA, NEW YORK, ASSIGNOR TO ECLIPSE TEXTILE DEVICES, INC., OF ELMIRA HEIGHTS, NEW YORK, A CORPORATION OF NEW YORK.

YARN CLEANER.

Application filed January 3, 1924. Serial No. 634,131.

To all whom it may concern:

Be it known that I, LOUIS B. HASBROUCK, a citizen of the United States, residing at Elmira, in the county of Chemung 5 and State of New York, have invented certain new and useful Improvements in Yarn Cleaners, fully described and represented in the following specification and the accompanying drawing, forming a part of the 10 same.

This invention relates to yarn cleaners and aims to provide a simple and effective device for removing impurities of all sorts from a traveling yarn.

15 An object of the invention is to provide a yarn cleaner in which all impurities removed from the yarn and any fibrous matter detached with them are continuously discharged from the cleaner without the use 20 of any mechanically-driven parts. A further object is to provide a yarn cleaner which will place the yarn under any desired tension so that no tension device need be used with the cleaner. A still further object is to provide a cleaner which will automatically adjust itself for operation upon 25 a yarn of any size.

I have found that if a yarn be drawn across a scraping edge and held in firm contact with said edge by a member opposed 30 to the edge and either urged toward the edge or separated from it by a distance less than the normal diameter of the yarn, the scraping action of the edge is effective to remove 35 small specks and particles adhering to the yarn as well as larger impurities. While slab catchers in which the yarn is drawn between two opposed edges have long been in use, it has heretofore proved impossible 40 to obtain an effective scraping action from such edges without removing fibrous matter from the yarn which winds around the yarn in front of the edges, becomes reattached to the yarn, and forms slabs which cause the 45 yarn to break in its passage through the cleaner. By the present invention I have overcome this difficulty and have produced a practical cleaner in which the yarn is effectively scraped without the danger of such 50 "balling up."

In accordance with the invention, either the member providing the scraping edge or the opposed member which holds the yarn in contact with this edge is given a continuous 55 movement in a direction longitudinal of

the edge, which has the effect of carrying away continuously all particles and fibrous matter scraped from the yarn, so that the fibrous matter does not wind about the yarn but is discharged continuously from the 60 cleaner with the particles which are detached from the yarn. In the form of the invention which I consider best, the yarn is drawn across the scraping edge in a direction oblique thereto so that the longitudinal movement of one of the members may be caused by the friction of the yarn against it. In this way the necessity of mechanically-driven parts is avoided.

65 In order to provide the most effective 70 scraping, both of the members between which the yarn is drawn may be provided with scraping edges. Thus, a yarn cleaner embodying the invention may be provided with a fixed arcuate blade and with a cylindrical blade which is rotatably mounted and positioned so that a portion of its edge is always opposed to and parallel with the edge of the fixed blade. The yarn is drawn between the opposed edges, and the blades 75 are yieldably urged toward each other so that the yarn contacts firmly with each edge. The yarn is guided to cross the edges in an oblique direction so that the cylindrical blade is continuously rotated by the friction 80 of the yarn traveling obliquely across its edge. This rotation of the blade causes a continuous longitudinal movement of its scraping edge which carries away all particles and fibrous matter scraped from the 85 yarn by the two edges.

90 In order that the invention may clearly be understood, I will describe in detail the specific yarn cleaner embodying it which is shown in the accompanying drawing, in 95 which:—

Fig. 1 is a view of the cleaner looking in the direction of the arrow 1 in Fig. 3;

Fig. 2 is a view of the cleaner looking in the direction of the arrow 2 in Fig. 3; 100

Fig. 3 is an enlarged transverse section of the cleaner taken on the line 3—3 of Fig. 1; and

Fig. 4 is a longitudinal section of the cleaner taken on the line 4—4 of Fig. 2. 105

The cleaner illustrated has a supporting plate 10 on which are mounted a plurality of cleaning units 11, 12, 13 and 14, each of which provides a fixed scraping edge and a movable scraping edge. The plate 10 has 110

a flange 15 to which is secured a supporting bracket 16. In order that the plate 10 may be tipped laterally at any desired angle to the horizontal, the bracket 16 is provided 5 with a pin 18 projecting at one end of the plate 10 and adjustably secured by means of a set screw 19 in a socket 20 at the outer end of a supporting arm 21. A traveling yarn A is guided across the plate 10 in a 10 longitudinal direction by a front guide 22 and a rear guide 23. In its travel across the plate 10 the yarn A passes between the scraping edges of each of the units.

As the cleaning units are alike, a description 15 of one of them will suffice. The unit 11 has a fixed arcuate scraping blade 30 which is curved so as to lie in a cylindrically curved surface whose axis is perpendicular to the plate 10. The blade 30 has at its inner edge an external flange 31 which is attached to the plate 10 by means of screws 32, along the periphery of a semi-circular recess 33 in the plate. The blade 30 is bevelled at 34 on its convex surface so that its outer 20 edge 35 is sharp. This edge 35 which has the form of an arc of a circle constitutes the fixed scraping edge of the unit.

By reference to Fig. 4 it will be seen that the position of the blade 30 on the plate 10 30 is such that a yarn traveling in a straight line from the front guide 22 to the rear guide 23 passes across its scraping edge 35 in an oblique direction, and that particles projecting from the yarn are brought into contact with the concave side of the blade 30.

The movable scraping blade 40 of the unit 11 has the form of a cylindrical flange depending from a disc 41. The blade 40 and the disc 41 together form an inverted cup-shaped member which has a hollow upwardly extending axial sleeve 42 rotatably mounted on a depending pin 43 secured in the outer end of a bracket 44 which may be formed integral with the plate 10. The pin 43 is co-axial with the fixed blade 30. The sleeve 42 provides a long bearing against the pin 43, preventing the cup-shaped member 40, 41 from tilting. The lower end of the pin 43 projects only a small distance below the disc 41 so that fibrous matter scraped from the yarn does not catch on this pin.

The blade 40 is bevelled on its convex surface at 45 so that its lower edge 46 is sharp. 55 This edge 46 is circular and constitutes the movable scraping edge of the unit. The circular edge 46 has the same radius as the arcuate edge 35, and the pin 43 is so positioned that a portion of the edge 46 is opposed to and parallel with the fixed edge 35. The distance between the edges 46 and 35 60 may be varied by sliding the axial extension 42 along the pin 43. The edge 46 is normally urged toward the edge 35 by the weight of the cup-shaped member 40, 41.

Behind the fixed blade 30 of the unit 11 is a pin 50 whose upper surface is located so as to guide the yarn A in a straight line from the front guide 22 toward the rear guide 23.

The other units are like the unit 11 which has been described, except that there is no guiding pin behind the rear unit 14, as the rear guide 23 is close to this unit.

The operation of the cleaner which has 75 been described is as follows:—The device is threaded by dropping a yarn into the recesses of the front and rear guides 22, 23. As soon as a pull is applied to the yarn to draw it forward through the cleaner, the 80 yarn is brought against the bevelled edges 34 and 45 of each unit and raises the cup-shaped members 40, 41 of each unit sufficiently to enable the yarn to enter between the scraping edges 35 and 46. The path of the 85 yarn is best shown in Figs. 1 and 4 where it will be seen that the yarn passes between the scraping edges of each unit at a point B, crossing each edge obliquely at this point. As the scraping edges are urged together 90 by the weight of the cup-shaped member, both of them contact firmly with the yarn at the point B. Since the yarn lies along a chord of the circle in which the movable edge 46 lies, it touches this edge at another 95 point C. The point C is, however, in front of the front end of the fixed blade 30 and in consequence the yarn is not pressed against the edge 46 at this point, and substantially 100 no fibrous matter is removed from it until it passes between the two edges at the point B. At this point any particles or irregularities 105 projecting from the yarn encounter the concave surfaces of the fixed and movable blades 30, 40. The result is that if any such particles catch on the edges of the blades the yarn is deflected downwardly from its course of travel. The pins 50, and the rear 110 guide 23, however, prevent the yarn from moving laterally far enough to lose contact with the fixed edges 35 of any of the units. The slight lateral movement given to the 115 yarn in this manner as it crosses between the edges makes the scraping action of the edges more effective.

The friction between the yarn and the edge 46 of each unit causes a continuous longitudinal movement of each edge 46 which is permitted by rotation of each cup-shaped member 40, 41 about its supporting pin 43. As the yarn passes between the scraping edges of the units, impurities of all sorts are scraped from it. The impurities removed by the edges of each unit, and all fibrous matter which may be removed from the yarn with them, follow the longitudinal movement of the scraping edge 46 of that unit. Some of the particles fall from the scraping edges 46 as soon as they are free 125 from the yarn. The recesses 33 in the plate 130

10 permit such particles to drop freely from the cleaner. Other particles and some fibrous matter are rolled along between the edges 46 and 35 until they reach the rear 5 end of the blade 30 where they fall from the cleaner. All particles and any fibrous matter scraped from the yarn are, therefore, continuously discharged from the cleaner.

The firmness of the contact of the scraping 10 edges with the yarn and the tension applied to the yarn may be regulated either by changing the angle of the plate 10 to the horizontal or by varying the number of weight discs 51 placed on top of the disk 15 41 of each unit. In this manner the pressure on the yarn is adjusted so that the edges contact with the yarn as firmly as possible without placing the yarn under sufficient tension to cause it to break.

20 Many changes may be made in the form and arrangement of the parts of the specific embodiment illustrated without departing from my invention. I wish it understood, therefore, that the invention is not confined 25 to particular features of the embodiment shown, except in so far as is specified in the claims which follow.

What I claim is:

30 1. A yarn cleaner for removing particles from a traveling yarn, comprising means providing a scraping edge, means for guiding the yarn across said edge so that it scrapes particles from the yarn, and continuously moved means for carrying away 35 from the line of travel of the yarn the particles and fibrous matter scraped off by the edge.

2. A yarn cleaner for removing particles 40 from a traveling yarn, comprising means providing a scraping edge, means for guiding the yarn across said edge so that it scrapes particles from the yarn, and continuously moved means actuated by the travel of the yarn for carrying away from 45 the line of travel of the yarn the particles and fibrous matter scraped off by the edge.

3. A yarn cleaner for removing particles 50 from a traveling yarn, comprising a member providing a scraping edge, means for guiding the yarn across said edge, and a member opposed to said scraping edge, engaging the yarn, and holding the yarn in firm contact with said edge, one of said members being continuously moved in a direction longitudinal of the scraping edge to carry away impurities and fibrous matter scraped from the yarn by the edge.

4. A yarn cleaner for removing particles 60 from a traveling yarn, comprising a member providing a scraping edge, means for guiding the yarn across said edge, and a member opposed to said scraping edge, engaging the yarn, and separated from said edge by a distance less than the normal diameter of the yarn, one of said members

being continuously moved in a direction longitudinal of the scraping edge to carry off particles and fibrous matter scraped from the yarn by the edge.

5. A yarn cleaner for removing particles 70 from a traveling yarn, comprising a member providing a scraping edge, means for guiding the yarn across said edge, a member opposed to said scraping edge, one of said members being continuously moved in 75 a direction longitudinal of the scraping edge, and means for yieldably urging said members toward each other so that the yarn is held in firm contact with the scraping edge.

6. A yarn cleaner for removing particles 80 from a traveling yarn, comprising a member providing a scraping edge, a member opposed to said scraping edge, means for guiding the traveling yarn between said 85 members and across said edge in a direction oblique thereto, and a mounting for one of said members arranged to permit such member to move in a direction longitudinal of the scraping edge under the 90 effect of the friction between such member and the yarn.

7. A yarn cleaner for removing particles 95 from a traveling yarn, comprising a member providing an arc-shaped scraping edge, a member opposed to said scraping edge and in contact with the yarn, means for guiding the traveling yarn across the scraping edge in a direction oblique thereto, and a mounting for one of said members permitting rotation thereof about an axis concentric with the scraping edge under the 100 effect of the friction between the yarn and said member.

8. A yarn cleaner for removing particles 105 from a traveling yarn, comprising a member providing an arc-shaped scraping edge, a rotatably mounted member opposed to said scraping edge, and means for guiding the traveling yarn across the scraping edge 110 and between said members in a direction oblique to the scraping edge so that the rotatably mounted member is rotated by the friction of the yarn against it and in its rotation carries off particles and fibrous 115 matter scraped from the yarn by the edge.

9. A yarn cleaner for removing particles 120 from a traveling yarn, comprising two members providing opposed scraping edges, and means for guiding the yarn between 125 said edges in a direction transverse thereto, one of said members being continuously moved in a direction longitudinal of its scraping edge to carry away the particles and fibrous matter scraped from the yarn.

10. A yarn cleaner, comprising two members providing opposed parallel scraping edges which are separated by a distance less than the normal diameter of the yarn, and means for guiding the yarn between 130

said edges in a direction transverse thereto, one of said members being continuously moved in a direction longitudinal of its scraping edge to carry off particles and fibrous matter scraped from the yarn.

11. A yarn cleaner for removing particles from a traveling yarn, comprising two members providing opposed scraping edges, and means for guiding the yarn between 10 said edges in a direction transverse thereto, one of said members being continuously moved in a direction longitudinal of its scraping edge, and means for yieldably urging said members toward each other so 15 that their scraping edges contact firmly with the yarn.

12. A yarn cleaner for removing particles from a traveling yarn, comprising two members providing opposed scraping edges, 20 means for guiding the traveling yarn between said scraping edges in a direction oblique to them, and a mounting for one of said members arranged to permit such member to move in a direction longitudinal 25 of its scraping edge under the effect of the friction between its scraping edge and the yarn.

13. A yarn cleaner for removing particles from a traveling yarn, comprising a fixed 30 blade having an arc-shaped edge, a rotatably mounted cylindrical blade having a circular edge, a portion of which is opposed to said arcuate edge, and means for guiding the traveling yarn so that it enters between 35 said edges from the concave side of the blades and crosses the edges obliquely.

14. In a yarn cleaner for removing particles from a traveling yarn, a scraping edge 40 which is continuously moved in a longitudinal direction, and means for guiding the traveling yarn transversely across said scraping edge and for restraining said yarn against lateral movement in the direction of movement of said edge.

15. In a yarn cleaner for removing particles from a traveling yarn, a member providing a scraping edge, means for guiding a traveling yarn across said edge in a direction oblique thereto, and a mounting for 50 said member arranged to permit such member to move in a direction longitudinal of the scraping edge under the effect of the friction between the scraping edge and the yarn.

16. A yarn cleaner for removing particles from a traveling yarn, comprising a rota-

tably mounted cylindrical blade having a scraping edge lying in a circle, means for guiding the traveling yarn across said edge in a straight line forming a chord of said circle, and means for holding the yarn in firm contact with said edge at one of the points at which it crosses the edge.

17. A yarn cleaner for removing particles from a traveling yarn, comprising spaced 60 yarn guides, means engaging the yarn at a point between said guides, and a rotatably and slidably mounted cylindrical blade having a circular edge crossing and resting on the yarn at a point opposite said engaging means.

18. A yarn cleaner for removing particles from a traveling yarn, comprising a fixed blade having an arcuate edge, a depending pin located above said blade and coaxial 75 with said edge, an inverted cup-shaped member rotatably mounted on said pin and having a circular scraping edge, a portion of which is opposed to said arcuate edge, and means for guiding the yarn between said 80 edges in a direction oblique to them.

19. A yarn cleaner for removing particles from a traveling yarn, comprising a fixed blade having an arcuate edge, means for guiding a yarn so that it crosses said edge 85 obliquely from the concave side of the blade, a depending pin located above said blade and coaxial with said edge, and an inverted cup-shaped member rotatably and slidably mounted on said pin and having a circular 90 scraping edge resting on the yarn at the point where the yarn crosses the edge of the fixed blade.

20. A yarn cleaner for removing particles from a traveling yarn, comprising a supporting plate containing a semi-circular recess, a curved blade secured to said plate along the edge of said recess and having an arcuate edge, a bracket extending from said plate to a point over the axis of said blade, a pin depending from said bracket and coaxial with the edge of said blade, and an inverted cup-shaped member having a long upwardly projecting sleeve rotatably mounted on said pin and having a depending cylindrical flange terminating in a scraping edge, a portion of which is opposed to and parallel with said arcuate edge.

In testimony whereof I have hereunto set my hand.

LOUIS B. HASBROUCK.
